UNITED STATES PATENT OFFICE.

GEORGE M. BATES, OF LEBANON, MISSOURI.

PAN-SCRAPER.

975,599.

Specification of Letters Patent. Patented Nov. 15, 1910.

Application filed September 10, 1909. Serial No. 517,070.

To all whom it may concern:

Be it known that I, GEORGE M. BATES, citizen of the United States, residing at Lebanon, in the county of Laclede and State of Missouri, have invented certain new and useful Improvements in Pan-Scrapers, of which the following is a specification.

This invention relates to culinary implements and refers particularly to an improved scraper to render the cleaning of cooking vessels easy.

An object of this invention is to provide a hand implement which is so formed as to present angular edges to accommodate the implement to the angles formed between the bottom and the sides of cooking vessels to enable the scraping of the same and the removal of all of the adhering particles incidental to the burning or the adhesive qualities of the substances which have been placed in such vessels.

The invention has for a further object the provision of an implement of this character which is so formed that the same can be easily held within the hand in a rigid position and be reciprocated by the action of the hand within vessels which are comparatively small.

The invention has for a still further object the provision of a scraper of this character which may be stamped upon a single portion of sheet metal by the single action of the cutter to thereby produce a sanitary as well as an economically produced article which occupies but small space so that the same can be utilized by the public to great advantage.

Other objects and advantages and the peculiar formation of the implement will be more clearly brought out in the following description and accompanying drawings.

For a full understanding of the invention reference is to be had to the following description and accompanying drawings, in which:

Figure 1 is a side elevation of the improved culinary implement, Fig. 2 is a perspective view of the same as applied to a pan, the pan being disclosed in dotted lines, and Fig. 3 is an edge view taken along the bottom edge of the implement as disclosed in Fig. 1.

Corresponding and like parts are referred

to in the following description and indicated in all the views of the drawings by the same reference characters.

In the drawings, in which is disclosed an embodiment of the invention and in which like parts are designated by the same numeral characters throughout the views, the reference numeral 10 designates a sheet of metal which is of flattened formation and so stamped as to form a rounded edge 11 at one end thereof, the edge being curved into substantially semi-elliptical formation and terminated in a substantial straight lower edge 12, which merges into the curved edge 11 to form a continuation thereof and to dispose a rounded corner, as at 13, upon the sheet of metal 10. The edge 12 is abruptly terminated at the opposite end of the implement which is cut to form a diagonal edge 14, disposed at an obtuse angle to the edge 12, the edge 14 being terminated in a point 15 formed by the cutting away of the upper edge of the implement to form a straight side 16. The point 15 is formed by the disposing of the edge 16 in an acute angle to the edge 14, the point 15 being adapted for engagement in corners and crevices in cooking utensils where the rounded corners are not accessible. The upper edge of the body portion, or sheet of metal 10, is cut away to provide inwardly converged edges 17 and 18 for the purpose of effecting the formation of corners 19 and 20, varying in an angular formation as is disclosed in Fig. 1, owing to the disposition of the edges 17 and 18 with respect to the curved end 11 and the upper edge 16. At one corner of the body portion, an aperture 21 is stamped for the purpose of engaging the implement upon a nail or the like, when it is desired to be conveniently hung up when not in use.

The use of the device is apparent from Fig. 2 wherein the implement is disclosed within a pan 22 and is engaged so as to dispose the point 15 at the adjacent edges of the bottom of the pan and the sides thereof, the sides or edges 14 and 16 extending from the point 15 being engaged respectively upon the bottom of the pan and the side thereof against the inner faces of the same.

The curved edge 11 adapts the plate 10 to the hand when grasped thereabout and when the point 15 is to be employed. The

corner 20 forms a projection from the plate 10 by the cutting away of the plate to provide the inwardly converged edges 17 and 18. The projection 20 thus forms a continuation of the curved edge 11 and serves to protect the hand from engagement against the wall of the vessel in which the scraper is employed. The scraper is disclosed in Fig. 2 in position to be operated in this manner. The thumb or a finger may be engaged beneath the edge 18 to further brace the device. When in this position the implement is vibrated in order to engage with the adhesive substances formed in the interior 15 of the receptacle or pan when such particles are removed. Should the vessel or receptacle be of a shape other than that disclosed in Fig. 2, the implement would be turned to the desired angle until the corresponding 20 point or sides were found to engage snugly between the bottom and the sides of the receptacle. It is thus observed that with a device of this nature, cooking utensils of practically any formation may be very readily cleansed as the angled sides and the 25 points formed, by reason of the disposition

of the sides, will be engaged in any crevices or corners formed in the receptacle.

Having thus described the invention what is claimed as new is:

A scraper including a sheet of metal stamped to form a point at its lower end, the edges of the sheet extending upwardly from the point at an acute angle, one of the edges terminating in an inwardly beveled edge which in turn merges into a second inwardly beveled edge extending outwardly from the body of the sheet at an obtuse angle to the first inwardly beveled edge, the second beveled edge extending outwardly to a rounded upper edge for the reception of the hand of the operator, the opposite side of the sheet having a diagonal edge extending downwardly and inwardly from the adjacent end of the upper rounded edge to the opposite lower edge terminating in a point.

In testimony whereof I affix my signature in presence of two witnesses.

GEORGE M. BATES. [L. S.]
